UNITED STATES PATENT OFFICE.

PAUL RYBÁRSKY, OF HOBOKEN, NEW JERSEY.

KNIFE-SHARPENER.

1,111,273.

Specification of Letters Patent. Patented Sept. 22, 1914.

Application filed April 28, 1914. Serial No. 834,964.

To all whom it may concern:

Be it known that I, PAUL RYBÁRSKY, a subject of the Emperor of Austria-Hungary, residing at Hoboken, in the county of Hudson and State of New Jersey, have invented certain new and useful Improvements in Knife-Sharpener, of which the following is a specification.

This invention relates to new and useful improvements in knife sharpeners.

The primary object of this device is to provide a cheap and inexpensive means for sharpening all kinds of knives and cutting edges, the same being hand operated and of small dimensions.

A further object is to provide a knife sharpener that may be easily carried in the pocket or in a tool box and consisting of but few parts while being highly efficient in the sharpening operation.

A still further object is to provide a convenient form of handle for adjustably-mounting sharpening bars and affording a convenient means for applying said bars to the surface to be sharpened.

With these general objects in view and others that will appear as the nature of the invention is better understood, the same consists in the novel combination and arrangement of parts hereinafter fully described, illustrated in the accompanying drawings, and pointed out in the appended claim.

In the drawings forming a part of this application and wherein like numerals of reference designate corresponding parts throughout the several views: Figure 1 is a perspective view of the device. Fig. 2 is a longitudinal central sectional view through the bar-carrying portion thereof and illustrating a knife positioned for sharpening, and, Fig. 3 is a top plan view of the same showing the knife in a different sharpening position.

Referring more in detail to the drawings, the invention primarily consists of a handle 10 provided at one end with a perforation 11 adapted to receive some of the fingers of the hand of the operator while at the opposite end of the handle a housing 12 is provided having an opening 13 therethrough positioned longitudinally of the handle 10 and in substantial alinement with a curved shoulder 14 positioned inwardly of the housing. Two sharpening bars 15 are positioned within the housing opening 13 and crossing

each other in an X-shaped formation having one end of each seated upon the shoulder 14. An adjusting screw 16 threaded through a perforation 17 of the housing wall bears against the adjacent one of the sharpening bars and whereby the said bars are retained within the housing.

The complete operation of the device will be apparent in that the bars 15 adapted for sharpening the knives are formed of extremely hard steel and are positioned within the opening 13 and retained in the desired angular relations by means of the screw 16, whereupon the cutting edge 18 of the knife 19 which is desired to be sharpened is placed between the sharpening bars as best illustrated in Fig. 3, and with the knife edge 18 engaging the sharpened adjacent edges 20 of the bars, a longitudinal movement being imparted to the knife and thereby forcing its edge between said bar edges and in contact therewith, and thus sharpening the knife edge. The handle 10 is adapted to be grasped in the hand and for better retaining the same against turning, one or more of the fingers may be positioned within the longitudinal slot 11 and whereby the sharpening bars may be reciprocated over the edge for the purpose of sharpening the same.

The bars 15 are preferably provided on each of their longitudinal edges with similar sharpened corner edges 20 so that the said bars are rendered reversible in the positioning housing 12.

While the employment of hardened steel sharpening bars is preferable, it will be understood that other forms of rifles, hones, or any desired forms of sharpening bars may be readily employed.

While the forms of the invention herein shown and described are what are believed to be preferable embodiments thereof, it is nevertheless to be understood that various forms and modifications may be resorted to which fall within the spirit and scope of the invention as claimed.

What I claim as new is:—

A device of the class described, comprising a handle and a curved shoulder spaced inwardly from one end thereof, a housing substantially rectangular in cross-section mounted upon said handle outwardly of said shoulder upon the same side thereof and having a longitudinal opening therethrough greater than the width of said

shoulder in alinement with the said shoulder, sharpening bars having cutting edges positioned crossing each other within the opening of said housing and with their inner ends seated upon said shoulder and spaced from the outer wall of said housing, an opening through the wall of said housing adjacent to said shoulder, and a set screw threaded in said opening and adapted for

engaging the face of the adjacent one of 10 said bars.

In testimony whereof I affix my signature in presence of two witnesses.

PAUL RYBÁRSKY.
